(57) **CLAIM**

The ornamental design for a chair shell, as shown and described.

DESCRIPTION

This application is related to the following application: U.S. design patent application Ser. No. 29/368,197, filed Aug. 19, 2010, the entire disclosures of which are incorporated herein by reference.

FIG. 1 is a perspective view of the chair shell showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The broken lines in FIG. 1 represent environmental structure and form no part of the claimed design.

The broken lines in FIGS. 2 and 7 represent an internal boundary of the claimed design; the broken lines in FIGS. 2 and 7 form no part of the claimed design.

The area within the broken lines in FIG. 7, a portion of which area is also shown in FIG. 2, forms no part of the claimed design.

1 Claim, 4 Drawing Sheets
